UNITED STATES PATENT OFFICE.

WILLIAM WIESLER, OF CLEVELAND, OHIO.

DESIGN FOR A HANGING FLOWER-POT.

No. 38,004.

Specification for Design.

Patented May 8, 1906.

Application filed March 20, 1906. Serial No. 307,120. Term of patent 7 years.

To all whom it may concern:

Be it known that I, WILLIAM WIESLER, a citizen of the United States, residing at Cleveland, in the County of Cuyahoga and State of Ohio, have invented a new and original Design of a Hanging Flower-Pot, reference being had to the accompanying drawing, forming part thereof, and in which the figure is a side elevation showing the design of the flower-pot.

I claim—
The ornamental design of a hanging flower pot, as shown.

WILLIAM WIESLER.

Witnesses:

R. B. MOSER,
C. A. SELL.
